UNITED STATES PATENT OFFICE.

ARCHIBALD MONTGOMERY, OF NEW YORK, N. Y.

COLLAR.

1,057,259.

Specification of Letters Patent.

Patented Mar. 25, 1913.

Application filed April 6, 1910. Serial No. 553,679.

To all whom it may concern:

Be it known that I, ARCHIBALD MONTGOMERY, a citizen of the United States, and resident of New York city, in the county of 5 Kings and State of New York, have invented certain new and useful Improvements in Collars, of which the following is a specification.

In the manufacture of collars, more 10 especially those of the fold-over type, various efforts have heretofore been made to provide a substitute for one of the closed slot end button holes of ordinary type, in order that the collar may be attached to the front 15 shirt stud at all times easily and without force being required to pull the second end button-hole over the stud after the first end is in place. In doing away with the closed slot button-hole, as for example by substituting a slot open at one end, among the necessary requirements it is to be provided, 20 that the shirt stud may be inserted in the open end of the slot without bending the collar at or near the slot; that the open slot 25 may be concealed from view when the collar is in position; that the structure of the collar may not be weakened so that it will be likely to bend or twist and fail to maintain its adjusted position; that the stud may be 30 readily secured in and removed from the open slot; and that the stud may be firmly positioned against slipping out of the slot 35 when the collar is in position.

While the above stated requirements have 35 been met in part it is the object of my invention to provide a collar wherein there is substituted for one of the closed slot end button-holes an open slot of novel form and construction so positioned that the shirt stud 40 may be slipped in or out without effort, and without bending the collar, and leading to a terminal stud seat or hole wherein the stud may be firmly positioned against accidental removal but from which it may readily be 45 removed when it is so desired to do. The slot is concealed from view when the collar is in place and the structure of the collar is of necessary and desired strength.

Having thus described my invention and 50 the objects to be secured thereby, I will describe in detail a particular form of embodiment thereof in connection with the accompanying drawing, wherein there is shown a view in elevation of the front ends of a 55 turn-over collar provided at one end with an open slot embodying my invention.

As shown in the drawing one end A of a turn-over collar, which is that end provided with an extended flap and customarily secured in place after the other end B, is provided with a slot 1 having one end open, the entrance 2 to the slot being substantially parallel with the upper and lower edges of the collar and located on the end edge of the extended flap of the collar band. The 60 slot 1 extends inwardly of the end of the collar at the same time curving downward until at a desired point, it is again directed toward the end of the collar and joins a terminal stud seat or hole 3 which is preferably 65 round as shown. This stud hole or seat is located in substantially the same position as would be the outer end of a closed slot button hole were such form used, this position giving the desired adjustment of 70 the collar when in place. The open end or entrance 2 of the slot 1 is comparatively broad, the sides of the slot converging as it extends inward and downward until at that portion 4 of the slot adjacent the stud 75 hole the sides of the slot are substantially contiguous. The inner end of the slot 1 in the form shown joins the stud hole below the central line thereof and preferably at one side. The portion of the collar band 80 through which the slot 1 passes is preferably reinforced to a desired extent by an additional thickness of material, a reinforced portion being indicated in dotted lines and denoted C.

It will readily be seen that after the end B of the collar has been secured in position on the stud, the end A may be brought over and as the extended flap of the band of the collar is inserted under the turn-over of the 95 end B, the stud may readily pass into the entrance of the slot and be guided into position in the stud hole or seat, a minimum effort and slight degree of care being necessary to effect the entire operation. The stud 100 being once positioned in the stud hole or seat its accidental removal therefrom is prevented both by the fact that the end of the collar must be pushed slightly upward since the slot joins the stud hole preferably below the 105 central line thereof, and by reason of the contiguous sides of the slot adjacent the stud hole. It may as readily be seen that a slight directed movement of the collar, such as would not accidentally occur, will serve to 110 unseat the stud and cause it to readily pass out of the slot. The natural strain on the

2
collar when in place tends both to hold the stud in position in the stud hole and to assist in its passage out of the slot when unseated.

- 5 While I have herein shown a form of collar embodying my invention it will be readily understood by those skilled in the art that changes and modifications may be made in carrying out the same without de-
10 parting from the spirit of my invention or the scope of the claim hereto appended.

I claim:

A turned-down lock-front collar having the usual locking tab, said tab having a

buttonhole comprising a slit extending in- 15 wardly through the vertical edge of the free end of the tab and thence downwardly and reversely curved toward the free end, and a recess located at the end of said slit for the reception of the shank of a collar button. 20

Signed at New York city in the county of New York and State of New York this 30th day of March A. D. 1910.

ARCHIBALD MONTGOMERY.
